UNITED STATES PATENT OFFICE.

OLOF ANDERSON, OF CHICAGO, ILLINOIS.

DESIGN FOR A CASING FOR JEWELERS' BLOWPIPES.

SPECIFICATION forming part of Design No. 27,913, dated November 30, 1897.

Application filed July 31, 1897. Serial No. 646,709. Term of patent 3½ years.

To all whom it may concern:

Be it known that I, OLOF ANDERSON, a subject of the King of Sweden and Norway, residing at Chicago, in the county of Cook and State of Illinois, have invented and produced a new and original Design for a Casing for Jewelers' Blowpipes, of which the following is a specification, reference being had to the accompanying drawing, in which the figure 10 represents a view in side elevation of a casing of a blowpipe, showing my design.

The leading feature of my design consists in a cylindrical or tubular portion A, one end of which is rounded, as at a, and has extending therefrom a tapered and curved tubular piece B, on the free end of which is an enlargement b. On the opposite end of the cy-

lindrical portion A from the rounded portion a is an annular cap C, outwardly rounded and having a milled periphery, as shown in 20 the drawing. Extending from the outer portion of the rounded part C is a tubular piece D, which is slightly tapered toward its junction.

Having described my invention, what I 25 claim as new, and desire to secure by Letters Patent, is—

A design for a casing for jewelers' blowpipes, substantially as herein shown and described.

OLOF ANDERSON.
